H. ZIMMERMAN

STITCHED BUFFING SECTION

Filed Nov. 29, 1926

UNITED STATES PATENT OFFICE.

HARRY ZIMMERMAN, OF FREMONT, OHIO.

STITCHED BUFFING SECTION.

Application filed November 29, 1926. Serial No. 151,487.

This invention relates to polishing or buffing disk sections or wheels.

This invention has utility when incorporated in multi-ply fabric disk sections as 5 stitch-assembled.

Referring to the drawings:

Fig. 1, is a fragmentary side elevation of a jack carrying a buffing wheel;

Fig. 2 is a side view, with parts broken 10 away, of plies as primarily assembled by diametrical stitching;

Fig. 3 is a fragmentary view of a stitched completed buffing disk or wheel section ready for assembly with other sections to 15 complete a buffing wheel; and

Fig. 4 is a view of a buffing disk section with parts broken away showing such as 20 built up from bias strips instead of from complete flat disks or pieced flat disks of fabric.

Drive belt 1 is shown as actuating pulley 2 fast on shaft 3, mounted in bearings 4 carried by base 5. This shaft 3 of the buffing jack has threaded terminals 6, and 25 adjacent the bearings 4, flanges 7.

A plurality of assembled multi-ply sections 8 may be placed upon the shaft 3 over the threaded end 6 and flange 9 placed in opposing relation to flange 7 and the plurality of sections assembled in a complete buffing wheel 10 by the operation of nut 11 in coaction with the threaded terminals 6 of the shaft 3.

Flat portions of fabric, as canvas duck in 35 the form of disks 12, 13 or pieced forms 14, 15, may be placed in superposed assembly with intersecting diametric stitchings 16, 17, 18, 19. The trimming of the disks or 40 plies to circular form may occur after this stitch assembly or even after the supplemental stitching. In the placing of these plies in overlapping relation, it is desirable 45 to have the warp and woof of said disks staggered as to their directions in the successive plies.

In the completion of the buffing section hereunder, stitching 20 extends inward parallel to the diagonal 18 to the diagonal 16 and then outward parallel to the diagonal 19.

50 Nesting with this V-stitching 20 are V-stitchings 21, 22 with such spacing as may be desired. In carrying out this invention, it is desirable to operate on alternate stitching diameters in that the diametrical stitchings serve as direction guides 55 for the sides of the V and location of the

apices of the V-stitching, making the symmetry more easy of attainment although it is to be understood that primarily value herein resides in the nested V-stitchings, 60 apart from whether diametrical stitching or other assemblies, be used. These V-stitchings may be of other than 90°. It would accordingly follow, if they were of 120°, three radially disposed series would be 65 proper instead of four as herein shown. The angle of the V-stitchings may be greater or less and the spacing between the nested V-stitchings may be varied according to the hardness of buffing section desired.

70 These nesting V-stitchings provide pockets 24, 25, 26, 27, of graduating depths, herein shown as from the periphery to a diameter. These pockets as distributed have a capacity 75 for retention of polishing or abrading matter, avoiding the necessity for as frequent replenishment of such, as may be required otherwise.

The several stitchings terminate peripherally of the section at such a degree of departure from tangency as to the periphery that there are open pockets with avoidance of intermediate hardness.

In the showing of Fig. 4, there is disclosure of the strips of tape or fabric, which, 85 as wound in a helix and flat, provide bias terminals at all times. Such strips laid parallel as to a common layer or ply may have the adjacent ply at an angle thereto, and such several bias strip plies may be embraced between outer plain plies and then assembled by the radial or diametrical stitching with the intermediate V-shaped stitching.

These are features contributing to uniformity in buffing section wear in operation. The stitchings have a maximum of effectiveness for uniformity of peripheral resistance. This is a result obtained with a minimum of stitching extent lineally with very material economy in thread and labor, notwithstanding there is resultantly produced a very superior buffing section.

What is claimed and desired to secure by Letters Patent is:

105 1. A buffing wheel section comprising a plurality of plies of fabric concentric disks, radial assembly stitching uniformly spaced, and supplemental V-shaped stitching providing a plurality of parallel peripherally 110 open pockets, the legs of each V-stitching being parallel to alternate radial stitchings

and the apex of each V-stitching being located on a radial stitching intermediate said alternate stitchings.

2. A buffing wheel section comprising a plurality of plies of fabric concentric disks, diametrical assembly stitching uniformly spaced, and supplemental V-shaped stitchings, having the apices thereof toward the

center of said disks as two oppositely directed series of V-stitchings upon a common 10 diameter diametrical stitching with the legs of said V-stitchings parallel to different diameter diametrical stitching.

In testimony whereof I affix my signature.

HARRY ZIMMERMAN.
